DESIGN FOR A SET OF CHESSMEN

Louis R. Hirschel, Brooklyn, N. Y.

Application July 20, 1946, Serial No. 131,756

Term of patent 3½ years

(Cl. D34—5)

To all whom it may concern:

Be it known that I, Louis R. Hirschel, a citizen of the United States, residing at Brooklyn, New York, in the county of Kings and State of New York, have invented a new, original, and ornamental Design for a Set of Chessmen, of which the following is a specification, reference being had to the accompanying drawing, forming a part thereof.

In the drawing:

Fig. 1 is a perspective view of the individual pieces of a set of chessmen showing my new design;

Fig. 2 is a front elevational view; and

Fig. 3 is a top plan view of the same.

Fig. 4 is a rear elevational view of the fourth figure shown in Fig. 2 of the same.

I claim:

The ornamental design for a set of chessmen, as shown.

LOUIS R. HIRSCHEL.
